Primary Examiner — Jack Reickel*Assistant Examiner* — Sydney M Evans(74) *Attorney, Agent, or Firm* — CP LAW GROUP PC;
Cy Bates(57) **CLAIM**

The ornamental design for an ornament hook, as shown and described.

DESCRIPTION

FIG. 1 shows front plan view of an ornament hook;
FIG. 2 shows a right plan view of the ornament hook;
FIG. 3 shows a left plan view of the ornament hook;
FIG. 4 shows a back plan view of the ornament hook;
FIG. 5 shows a top plan view of the ornament hook;
FIG. 6 shows a bottom plan view of the ornament hook; and,
FIG. 7 shows a perspective view of the ornament hook.
That which is represented by broken lines illustrates environmental subject matter only and does not form part of the claimed invention.

1 Claim, 7 Drawing Sheets(56)
